(57) **CLAIM**

The ornamental design for an in-vehicle monitor as shown and described.

DESCRIPTION

FIG. 1 is a perspective view of an in-vehicle monitor, showing our new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof; and,

FIG. 7 is a left side view thereof.

The translucent gray overlay and the broken lines in the figures show portions of the in-vehicle monitor that form no part of the claimed design.
